UNITED STATES PATENT OFFICE.

GUSTAV BURKHARDT, OF HOMER, ASSIGNOR OF ONE-HALF TO NATHANIEL BOWDITCH, OF AURORA, ILLINOIS.

WASHING-MACHINE.

SPECIFICATION forming part of Letters Patent No. 245,917, dated August 16, 1881.

Application filed June 9, 1881. (No model.)

To all whom it may concern:

Be it known that I, GUSTAV BURKHARDT, a citizen of the United States, residing at Homer, in the county of Champaign and State of Illinois, have invented new and useful Improvements in Washing-Machines, of which the following is a specification.

This invention consists in a washing-machine in which are combined a cylindrical base, 10 a conical hood secured above the base by upwardly-projecting arms, thereby creating an intervening space between the adjacent edges of the hood and the base, a conical perforated plunger beneath the hood, flap-valves arranged on the plunger opposite its perforations to close in an upward direction, a reciprocating plunger-rod guided in the hood, and a spring acting on the plunger-rod with a tendency to raise the plunger, so that if the whole 15 is placed in a tub containing the clothes to be washed, with the lower edge of the base resting on the clothes, a current of mixed air and water can be forced through the clothes by means of the plunger. Radial corrugated 20 rollers are applied to the plunger for pounding the clothes.

This invention is illustrated in the accompanying drawings, in which Figure 1 represents an inverted plan view. Fig. 2 is a vertical 25 cross-section on the line *xx*, Fig. 1. Fig. 3 is a similar section on the line *yy*, Fig. 1.

Similar letters indicate corresponding parts.

The letter A designates the base; B, the hood; C, the plunger; D, the valves; E, the plunger-rod; F, the spring, and G rollers or pounders.

The base A is cylindrical, and the hood B is secured thereto by vertical arms *h*, which project above the top edge of the base, where they are joined to the hood, thereby creating a space 30 between the adjacent edges of the base and the hood. Both the hood B and the plunger C have an approximately conical shape, and the plunger is beneath the hood, its normal position being within or directly beneath it. In

40 the plunger C are formed holes or perforations *k*, opposite to which are located the flap-valves D, these valves being hung on the inner or under surface of the plunger, as at *l*, to close in an upward direction, and resting on staples *n* 45 when open.

The plunger-rod E is guided in the hood B at the upper end of the hood, where the latter is provided with a tubular extension, *o*, and the spring F is coiled on the rod, one end of the spring bearing against the hood and the other end against a sleeve, *p*, fixed to the rod, so that the spring acts on the rod with a tendency to raise the plunger to its normal position.

The rollers G are corrugated respectively in a longitudinal direction, and are mounted loosely on radial shafts *q*, which are fixed to the plunger C at or near its lower edge, the shafts intersecting each other and being connected together by a central ring, *r*.

The clothes to be washed having been placed in a suitable tub with sufficient water to saturate the clothes, the apparatus is placed into the tub with the lower edge of the base A resting on the clothes, and then the plunger C is alternately depressed against the action of the spring F to bring it into contact with the clothes, and allowed to rise. In the descent of the plunger the valves D close and the plunger is filled with air, which is forced through the clothes, together with the water, while in the ascent of the plunger the valves open, thus allowing or facilitating such motion. By the action of the plunger the rollers G are caused to pound or beat the clothes, thus loosening the dirt.

What I claim as new, and desire to secure by Letters Patent, is—

The combination, substantially as hereinbefore set forth, of the cylindrical base, the conical hood, the conical perforated plunger beneath the hood, the flap-valves arranged on the plunger opposite its perforations to close in an upward direction, the radial corrugated rollers or pounders of the plunger, the reciprocating plunger-rod, and the spring acting on the plunger-rod with a tendency to raise the plunger, as described.

In testimony whereof I have hereunto set my hand and seal in the presence of two subscribing witnesses.

GUSTAV BURKHARDT. [L. S.]
